O. & Z. W. AVERY.

Pendulum Scales.

No. 17,252.

Patented May 12, 1857.

UNITED STATES PATENT OFFICE.

Z. W. AVERY AND OTIS AVERY, OF BETHANY, PENNSYLVANIA.

SELF-INDICATING BALANCE.

Specification of Letters Patent No. 17,252, dated May 12, 1857.

To all whom it may concern:

Be it known that we, Z. W. Avery and Otis Avery, of the town of Bethany, in the county of Wayne and State of Pennsylvania, 5 have invented a new and useful Self-Indicating Scale or Balance by Which the Amount of Weight Placed in the Dish is at Once Shown on the Scale-Beam; and we do hereby declare that the following is a full, 10 clear, and exact description of the construction and operation of the same, reference being had to the annexed drawings, and letters of reference marked thereon, making a part of this specification.

15 The nature of our invention consists in applying a rolling poise *a*, to the top of the balance beam *b*, both the poise *a* and beam *b* being smooth so as to offer the least possible resistance to the poise *a*, as it rolls out on 20 the beam.

Figure 1 is a perspective view of the scale in which the rolling poise *a* is shown on the top of the beam *b*. The poise *a* is kept in 25 its position by the armature *c*, so arranged that the elevation of the beam *b* causes the poise *a* to roll out and balance whatever may be placed in the dish. The frame of the scale *g g g* has a standard sufficiently high to hold the upper end of the armature *c* and 30 allow a free sweep as it is carried out in the act of weighing. The armature carries an index *e*, which extends down a little below the poise *a*, to point out the amount of

weight on the graduated scale beam *b*. The letters marked on this drawing refer also to 35 the corresponding parts on the others. Thus *a* is the rolling poise, *b*, the graduated scale beam, *c*, the armature, *e*, the index at the end of the armature, *f*, the transverse piece on the end of the armature. *g g g* is the frame 40 of the scale, *h h*, the arrangement for keeping the pan or dish in its position.

Fig. 2 is a longitudinal elevation with dotted lines showing a continuation of parts.

Fig. 3 is a transverse section showing the 45 manner of connecting the upper end of the armature *c*, (represented by *f*.) with the standard.

Fig. 4 is a horizontal plan of the scales the dotted lines showing a continuation of parts. 50

Fig. 5 is a section through A, A, being a common arrangement for holding the pan.

Fig. 6 is a section of the rolling poise *a* showing its connection with the armature *c*.

What we claim as our invention and desire to secure by Letters Patent is--

The combination of the rolling poise *a*, with the smooth beam *b*, and the armature *c*, operating and arranged substantially in the manner and for the purpose hereinbefore set 60 forth.

Z. W. Avery.
OTIS Avery.
